CLAIM

The ornamental design for a display screen or portion thereof having a graphical user interface with a time slider for a map, as shown and described.

DESCRIPTION

The patent or application file contains at least one drawing executed in color. Copies of this patent or patent application publication with color drawing(s) will be provided by the Office upon request and payment of the necessary fee.

FIG. 1 is a first embodiment of a display screen or portion thereof having a graphical user interface with a time slider for a map showing my new design;

FIG. 2 is a second embodiment thereof; and,

FIG. 3 is a third embodiment thereof.

The broken dashed lines depict portions of the display screen or portion thereof having a graphical user interface with a time slider for a map in which the design is embodied that form no part of the claimed design. The contents of the area within the dashed lines presented in a dot-dash pattern form no part of the claimed design.
